ATTYS.

UNITED STATES PATENT OFFICE.

WILLIAM C. ROSSNEY, OF HYDE PARK, ASSIGNOR OF ONE-HALF TO MICHAEL J. SCANLAN, OF BOSTON, MASSACHUSETTS.

AUTOMATIC GAS-SUPPLY SHUT-OFF AND REGULATOR.

SPECIFICATION forming part of Letters Patent No. 449,178, dated March 31, 1891.

Application filed October 6, 1890. Serial No. 367,177. (No model.)

To all whom it may concern:

Be it known that I, WILLIAM C. ROSSNEY, of Hyde Park, in the county of Norfolk, State of Massachusetts, have invented certain new and useful Improvements in Automatic Gas-Supply Shut-Offs and Regulators, of which the following is a description sufficiently full, clear, and exact to enable any person skilled in the art or science to which said invention appertains to make and use the same, reference being had to the accompanying drawings, forming part of this specification, in which—

Figure 1 is a sectional elevation illustrating my improved device in use, and Figs. 2 and 3 sectional elevations showing modifications in the formation of the shut-off valve.

Like letters and figures of reference indicate corresponding parts in the different figures of the drawings.

My invention relates especially to means for regulating the supply of illuminating-gas to buildings and providing the same with a shut-off, whereby gas explosions may be prevented in case of fire in the building; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the body of the regulator, B the main gas-supply pipe, and C the water-pipe.

The gas-supply pipe B opens through the building-wall E in the usual manner.

The regulator-body A consists of a cylindrical metallic box, which is interposed in the supply B, and is provided with a removable cover b.

Within the body a chamber d is formed into which the supply B opens. In the top f of said chamber a cylindrical valve-seat g is mounted, the lower edge of said cylindrical seat being toothed or corrugated at h. In the bottom of said chamber a drip-pipe i opens.

A cup-shaped valve adapted to contain mercury and having its upper edge turned inward, forming an air-space k, is adjustably mounted on a stem m, which passes vertically

through the valve-seat g, and which is supported on the top f of the chamber by a cross-bar l. The upper end of the stem m is provided with a socket p, in which a ball q works, said ball being formed on the end of a vertically-arranged rod r, the outer end of which is disposed in a dome t on the cover b.

A horizontal partition v is arranged within the body A above the chamber d, and is provided with a centrally cylindrical opening x, through which a rod r passes. Around the walls of said opening a cylinder y is secured to the partition v, forming a liquid valve seat z, in which a valve 15 works, said valve being adjustably mounted on the rod r, which is screw-threaded at 16 for this purpose. A cylinder 17 is disposed on the partition v and forms a liquid seal 18 with the walls of the body A. A dome or gas-holder 19, adjustably mounted on the threaded portion of the rod r plays in said seal, weights 20 being disposed on said dome to adjust it in the liquid seal. A discharge-pipe 25 opens into the body A at the side opposite the main supply B and leads to the different rooms of the building. A pipe 26 passes through the partition v and opens within the cylinder 17, its upper end being 80 provided with a spring-pushed swinging valve 27. Said pipe then passes out through the wall of the body A adjacent to the discharge 25, and is extended horizontally until it nearly reaches the wall D, where it is provided with 85 a cock 29. Said pipe again passes horizontally by the regulator-body A and enters the gas-discharge pipe 25 at 30. The main supply B is tapped by a vertically-arranged pipe 31 near the wall D, said pipe being provided 90 with a shut-off cock 32 and a vent-cock 33. The pipe 31 then passes into the body A between the chamber-top f and the partition v and opens at 34 within the cylinder 17 under the dome-valve 19.

A vertically-arranged water-pipe H passes through the inner wall D and is connected with the water-supply pipe C. Said pipe H is so disposed that it will pass through the entries or exits of the building. A gas-pipe 100 35 is disposed within the pipe H and is surrounded with water. The lower end of said gas-pipe is connected by a pipe 36 with the main gas-supply B. Branch pipes 37 tap the pipe 35 at such points as it is desired to maintain a light. The burners 38 on said pipe are

protected by a metallic shield or hood 39, attached to the water-pipe II.

- In the use of my improvement gas from the main B passes into the chamber d through the valve-seat g into the main body A and out the discharge 25. Gas from the discharge-pipe 25 passes through the pipe 26 and into the body A under the dome 19. The pressure thereof causes said dome to raise or lower in its liquid seat 18, carrying with it the rod r, and opening or closing a valve j, thus automatically regulating the supply of gas to said discharge 25. The valve 15, sealing the opening through the partition v around the rod r, prevents the direct pressure of the gas from acting upon the dome 19, and causing the gas in said discharge-pipe to remain at a normal pressure. In case of fire in the building or if from other cause it is desirable to cut off the supply of gas the cock 32 in the pipe 31 is opened. This admits gas from the supply B at "street" pressure through said pipe 31 into the regulator A under the dome 19. Said dome is immediately forced upward by the increased pressure and carries with it the rod r, forcing the valve j tightly against its seat g, and cutting off the supply of gas to the discharge 25. At the same time the direct pressure of gas under the dome 19 from the pipe 31 drives the swinging valve 27 against its seat and closes the pipe 26, preventing any gas passing therethrough to the discharge-pipe 25. The spring-tension of the swinging valve is sufficient to hold said valve open against the regulated gas-pressure under the dome, permitting the escape thereof and the dome to descend to open the valve j when the pressure in the discharge 25 is reduced by the lighting of the burners. Such spring-tension is not, however, sufficient to resist the direct street-pressure admitted to the dome as above described through the pipe 31, and said swinging valve is thereby closed. The supplemental gas-pipe 35, being incased in a water-jacket, is protected from injury by heat or from the falling portions of the building, and a light may be retained therefrom illuminating the exits while the main supply of gas is shut off from the building. When it is again desired to turn on the gas, the cock 32 is closed, shutting off the direct pressure from the dome 19. Said pressure is then relieved to permit said dome to fall by opening the vent-cock 33 in the pipe 31. As the dome thus descends it opens the valve j and again admits a regulated supply of gas, as above described, to the discharge-pipe 25.
- I do not confine myself to the form of valve j and seat g described, as any suitable construction of valve may be employed.
- In Fig. 2 a hollow inverted-cone-shaped valve 40 is shown, which rests upon a knife-edge seat 41, mounted on the top f of the chamber d, in the same position as the valve-seat g described. Said valve 40 is swiveled at its apex to a rod 42, the upper end of which is hinged to a counterbalance-lever 43,

pivoted at 44 to a standard 45, secured in the chamber-top f. The opposite end of the lever 43, when this form of valve is employed, is pivoted to the rod r.

In Fig. 3 a hood-valve is shown. A seat 50 is constructed in practically the same form as the valve j, and is designed to be secured in the top f of the chamber d. The valve 51 is constructed in practically the same form as the valve-seat g described, excepting that its top is closed at 52 and is pivoted to the end of a lever 43, in the position of the stem 42 in Fig. 2.

Having thus explained my invention, what I claim is—

1. In a device of the character described, a gas-pressure regulator comprising a body or casing provided with a main supply-pipe, a discharge-pipe, a valve, and connected gas-actuated mechanism, in combination with a pipe connecting the discharge-pipe with said valve mechanism, and a pipe connecting said mechanism directly with the main supply-pipe, substantially as and for the purpose set forth.

2. In a device of the character described, a gas-pressure regulator provided with a main supply-pipe, a discharge-pipe, and a cut-off valve interposed between said pipes, in combination with a liquid-sealed hood on the stem of said valve, a pipe connecting said hood with the discharge-pipe, a spring-cushioned swinging valve in the mouth of said pipe, and a pipe connecting said supply-pipe with the hood, substantially as described.

3. In a device of the character described, the combination of a gas-pressure regulator, a supply and a discharge pipe therefor, a pressure-regulating cut-off valve in said regulator, a pipe connecting the discharge-pipe and valve-actuating mechanism, a pipe connecting said supply-pipe with the valve-actuating mechanism, and a cock and vent in said pipe, substantially as described.

4. In a device of the character described, a gas-pressure regulator and gas supply and discharge pipe therefor, in combination with a pipe connecting said discharge with the pressure-regulating mechanism, and a pipe connecting said supply with said mechanism, substantially as and for the purpose set forth.

5. In a device of the character described, the body A, provided with supply and discharge pipes, the valve j, hood 19, and respective seats, arranged substantially as specified, in combination with the pipe 26, provided with a valve 27, and connecting the discharge-pipe with said hood, the pipe 31, connecting the hood and supply-pipe and provided with a cock 32 and vent 33, substantially as described.

WILLIAM C. ROSSNEY.
